UNITED STATES PATENT OFFICE.

GEORGE B. BASSETT, OF BUFFALO, NEW YORK.

WATER-METER.

SPECIFICATION forming part of Letters Patent No. 530,743, dated December 11, 1894.

Application filed July 28, 1894. Serial No. 518,788. (No model.)

To all whom it may concern:

Be it known that I, GEORGE B. BASSETT, of Buffalo, New York, have invented a new and useful Improvement in Water-Meters, which improvement is fully set forth in the following specification.

This invention relates to improvements in water meters, and more particularly to disk water meters of that class as shown in Letters Patent No. 501,203, granted to me on the 11th day of July, 1893.

The objects of my present invention are principally to improve the construction and arrangement of the casing, disk chamber, and other points in the construction of these meters for the purposes of reducing the cost of manufacture, allowing the more ready assemblage and separation of parts, the draining of the meter when not in use, increasing the durability and efficiency and giving other advantageous results.

I will now proceed to definitely describe the manner in which I have carried out my invention and then claim what I believe to be novel.

In the drawings—Figure 1; is a central vertical section of my improved meter. Fig. 2; is an elevation of the same with the outer casing in section to show interior parts. Fig. 3; is a top plan view of the lower casing with disk chamber resting upon it. Fig. 4; is a top plan view of the lower casing. Fig. 5; is a detail sectional view of the disk spindle bearing. Fig. 6; is a detail view of the diaphragm and bearing piece for edge of disk. Fig. 7; is a top plan view of disk showing location of diaphragm and bearing piece for edge of disk.

Referring to the drawings, the working parts except the register are surrounded and contained in a separate outer case consisting of two parts 1 and 2 bolted together at their flanged meeting edges as at 3, (Figs. 3 and 4.)

4 is the stuffing box shaft protruding through stuffing box 5 where it may be attached to a register of any well known form mounted on outer casing 1. On the inner end of shaft 4 is permanently mounted the toothed gear wheel 6. The outer casing 2 contains both the inlet and outlet spuds 36 and 37, and also the radial partition 28 at right angles to the line of the spuds and which divides the space within casing 2 into two compartments

26 and 27, the inlet spud communicating with one compartment and the outlet spud with the other compartment.

55

The disk chamber consists of two parts 18 and 19 fastened together by screws and resting on the outer casing 2 and web 28, and held in place by the annular notch 30 cut in casing 1 which receives the annular projection of 60 plate 19 of the disk chamber. The space surrounding the disk chamber and between it and the outer case is thus divided into three compartments 25, 26 and 27.

In the spherical side wall of part 18 of the 65 disk chamber are located the inlet and outlet ports 32 and 35. Port 32 communicates with the compartment 25 and port 35 is covered by the hood 34 and communicates, through the elongated passage 33 in plate 19, with 70 compartment 26. At the apex of the conical end wall of part 18 is a spherical annular bearing for the disk ball 15 and an inclosed recessed chamber 13 in which is located the beveled bearing roller 22 mounted on the cylindrical sleeve 12 and held in place by the ring 23 sprung into a groove cut in sleeve 12, (Fig. 5). By this construction the disk spindle is retained in its circular path without undue wear or friction, and the disk and controlling spindle are entirely inclosed in the disk chamber and recess and thus maintained in static equilibrium. No adjustment is required to relatively center the disk spindle and its bearing roller. Between sleeve 12 and 80 shaft 11 is removably secured a bushing 24 (preferably of hard rubber) which may be readily removed and substituted when worn.

In the center of plate 19 which forms one end of the disk chamber is a spherical 90 socket or bearing for pivot ball 15 of the disk. The plate 19 has radially formed across its outer surface the web 29 which registers and rests upon the radial partition 28 of outer casing 2 thus sealing the inlet and outlet compartments 27 and 26 from each other. The holes 31 are formed in the annular projection of plate 19 to afford communication from the inlet compartment 27 and spud 36 to the compartment 25 and inlet port 32 and at the same 100 time to strain out any large foreign substances that otherwise might clog the working parts of the meter and also to break up the inflowing current of water so that it will pass into

the disk chamber through port 32 with a nearly uniform velocity at all points.

20 is a diaphragm or plate located between the inlet and outlet ports 32 and 35 and secured within the disk chamber by resting in a groove cut in the spherical side wall and end cone of part 18 and secured in place by the projection 21 which passes through the wall of the disk chamber and is riveted down.

10 To reduce the friction caused by the metallic web 16 of the disk against diaphragm 20 a strip 38 (preferably of hard rubber) is secured to the side surface of the diaphragm to receive the thrust of the disk.

15 Within the disk chamber is located the oscillating or nutating measuring disk composed of the metallic web 16 on each side of which are securely fastened the parts of the pivot ball 15 (preferably of hard rubber) by 20 the disk spindle 14 which is threaded into one section of the ball and has the annular collar 17 bearing against the other section.

The web 16 is slotted to receive the diaphragm 20 with bearing piece 38.

25 The intermediate gearing that communicates and reduces the motion from the spindle 14 of the nutating disk to the stuffing box shaft 4 is mounted on the disk casing. The shaft 11 is bent at its lower end to engage 30 the disk spindle 14 and it is held in place by being permanently driven into pinion 10. Pinion 7 and gear wheel 9 rotate about pin 8 which is permanently fastened into the disk casing.

35 A small hole 39 is formed in the spherical wall of the disk chamber at a point nearly ninety degrees from the diaphragm 20 and on the side of the inlet port 36 to facilitate the complete drainage of the disk chamber 40 where the meter is set in a vertical pipe with inlet spud 36 pointing downward.

In operation the water enters through spud 36 to the compartment 27, then passes through the holes 31 into compartment 25 and thence 45 into the measuring disk chamber through the inlet port 32. After passing through the disk chamber in a circular path and oscillating the measuring disk it passes out port 35 through elongated opening 33 to compartment 26 and 50 outlet spud 37. When the measuring disk continuously oscillates the spindle 14 travels in a continuous circular path and engages the bent end of shaft 11 rotating pinion 10 which engages with gear wheel 9 rotating pinion 7 which engages with gear wheel 6 rotating stuffing box shaft 4 and operating the register.

It will be seen by the arrangements and disposition of the parts that when the meter 60 is placed on a horizontal pipe all water will drain from it through inlet spud 36 except that contained in compartment 26, and when meter is placed on a vertical pipe all water will drain from it through inlet spud 36. It 65 will also be seen that as both the inlet and outlet spuds are wholly in part 2, part 1 on which is the register may be fastened to

it in any position and the register brought into a suitable position for reading irrespective of the position of the inlet and outlet 70 spuds.

Having thus described my invention, what I claim, and desire to secure by Letters Patent, is—

1. In a water meter, the combination with 75 a disk-chamber, of a bushing removably mounted in said disk chamber and forming a bearing for the intermediate gearing shaft, substantially as described.

2. In a water meter, the combination with 80 a separate outer surrounding case and a disk-chamber contained therein, of a bushing mounted in said disk-chamber and forming a bearing for the intermediate gearing shaft, 85 substantially as described.

3. In a water meter, the combination with 90 the disk-chamber, the disk and its spindle, of a bearing roller controlling the disk spindle, said roller being located in a chamber or recess formed by walls integral with the said 95 disk-chamber, substantially as described.

4. In a water meter, the combination with 100 a separate outer case, of a disk-chamber provided with a cone-shaped end and having a recess formed in the cone of said disk-chamber, 105 a disk and spindle in said chamber, and a bearing roller controlling the disk spindle and mounted in said recess, substantially as described.

5. In a water meter, the combination with 110 the disk-chamber having a conical end and an inclosed recess forming an integral part thereof, of a bearing roller for the disk spindle mounted in said recess and intermediate 115 gearing mounted on a pin fixed to the said 120 disk-chamber, substantially as described.

6. In a disk water meter, the combination with 125 an outer surrounding case having inlet and outlet openings, of a disk-chamber held in place in said outer case by an annular projection formed integral with one of the end cones of said disk chamber extending into an annular notch formed in the meeting flanges of said outer case, substantially as described.

7. In a disk water meter, the combination with 130 an outer surrounding case having inlet and outlet openings, of a transverse web and an inner disk-chamber so located as to divide the total space between the inner wall of said outer case and the outer wall of said disk 135 chamber into three compartments, substantially as described.

8. In a water meter, the combination with 140 a disk-chamber having a conical part provided with a web or fin radially disposed across its 145 outer side, of an outer surrounding case one part of which has a radially disposed partition that registers with said web, for the purposes specified.

9. In a disk water meter, an outer casing 150 provided with inlet and outlet spuds, and having a radially disposed partition at right angles to the center line of the inlet and outlet spuds, substantially as described.

10. In a water meter, the combination with a separate outer case, of a disk-chamber contained therein, a recess formed in one cone of said disk chamber, a bearing roller mounted 5 in said recess, a disk with spindle projecting into said recess, and a shaft projecting into said recess and receiving motion from said spindle, substantially as described.
11. In a disk water meter, the combination 10 with the outer casing having a radially disposed web and the disk chamber, of a radially disposed diaphragm in the disk chamber, a radially disposed web on one end of the disk chamber, registering with the web in the 15 outer case, said diaphragm and web being in the same plane, substantially as described.
12. In a disk water meter, the combination 20 with the outer casing having a radially disposed web and inlet and outlet spuds, and with the disk-chamber and a radially disposed diaphragm therein, of a radially disposed web on one cone of the disk chamber registering with a radially disposed web in the outer case, the diaphragm and web being at right angles to the center line of the inlet 25 and outlet spuds, substantially as described.
13. In a water meter, the combination with intermediate gearing permanently mounted on the end of the disk chamber, of a bearing roller for the disk spindle mounted in a recess within the end cone of the disk chamber, substantially as described. 30
14. In a water meter, the combination with a separate outer surrounding case containing inlet and outlet spuds, of the disk and disk- 35 spindle and a separate inner disk-chamber and recess, entirely surrounding the disk and disk-spindle and its bearing roller, thus maintaining an equal pressure on both sides of the disk ball, substantially as described. 40

In testimony whereof I have signed this specification in the presence of two subscribing witnesses.
